UNITED STATES PATENT OFFICE.

GEORGE WOODVINE, OF SHREWSBURY, ENGLAND.

MANUFACTURE OF SPRING PACKING-RINGS FOR PISTONS AND THE LIKE.

1,296,580.

Specification of Letters Patent.

Patented Mar. 4, 1919.

Application filed November 22, 1917. Serial No. 203,441.

To all whom it may concern:

Be it known that I, GEORGE WOODVINE, a subject of the King of Great Britain and Ireland, and a resident of Shrewsbury, in the county of Salop, England, have invented certain new and useful Improvements in the Manufacture of Spring Packing-Rings for Pistons and the like, and of which the following is the specification.

10 This invention relates to divided spring packing rings for pistons and the like; and has for its object to impart to such rings in an improved manner the necessary spring to cause them when in position on the piston, 15 to bear with the required uniform pressure against the inner wall of the cylinder in which the piston works.

Hitherto to attain this object such rings have been subjected to unequal compression 20 by hammering or rolling, the compression being greatest at the point opposite to the cut end and gradually diminishing toward these ends and being applied either to the internal or the external surface of the ring 25 according to whether it is desired to expand or contract the ring.

According to the present invention the ring is turned and bored concentric and also split as usual, and where it is desired to expand the ring it is then laid in a holder or die and the inner periphery subjected to pressure by pushing through the ring a broach or mandrel having on its periphery a series of projections arranged eccentric 35 to the body of the mandrel in such manner that the maximum projection bears on the inner surface of the ring at the point opposite to the cut ends thereof, the projections gradually diminishing from this point in 40 both directions until they finally disappear at points a little distance away from the part of the mandrel adjacent to the cut ends of the ring, the mandrel bearing on the ring at this part.

45 Thus on pushing the mandrel through the ring the metal on the inner surface thereof is indented and stretched by the projections in a gradually diminishing degree in both directions from the point opposite to the cut 50 ends and the desired spring is thus imparted to the ring.

Where it is desired to contract the ring it is placed around a solid holder or die, and a hollow broach with the eccentrically placed 55 projections on its inner periphery is used. Thus on pushing the broach over the ring

the projections are made to bear on the outer surface of the ring instead of the inner surface.

The broach or mandrel may be constructed in various ways. For example the projections thereon may take the form of a number of steel balls held in a groove which is eccentric to the body of the mandrel. Or the projections may be in the form of teeth gradually diminishing in effective radial depth from the maximum acting on the inner surface of the ring at the point opposite to the cut ends thereof, and held in recesses in the periphery of the mandrel. That is to say the teeth may be of gradually diminishing depth and the recesses uniform in sizes, or again the teeth may be of uniform depth and the recesses of varying depths.

Three sheets of explanatory drawings are 75 hereunto appended in which Figure 1 is a plan and Fig. 2 a vertical section showing an example of the improved means used to expand the packing rings, a second example is shown to a larger scale in plan in Fig. 3; 80 while Fig. 4 is a vertical section and Fig. 5 an inverted plan showing an example of the improved means used where it is desired to contract the packing rings.

As shown in Figs. 1 and 2 there is provided a hollow holder or die A having an internal stepped portion of such depth that a number of packing rings B may be laid therein, one above the other, the rings having been, of course, first turned and bored 90 concentric and also split as usual. The radial depth of the stepped portion of the holder A relative to the thickness of the rings B is such that, as shown, the internal diameter of the rings, when they are in position in the holder, is slightly less than the internal diameter of the lower portion of the holder. The rings B are held in place in the holder by a cover plate C. With this holder A there coacts a broach or mandrel 100 made in two portions D, E held together by studs G. The meeting edges of these two portions are so shaped as to form a groove H eccentric to the body of the broach in which groove are held a number of steel 105 balls J which form a ring of projections also eccentric to the periphery of the broach. To expand the rings B, the broach D, E is so forced through the holder A that the maximum projection J bears on the inner 110 surface of the rings in the holder, at the point opposite to the cut ends of the rings,

the projections gradually diminishing from this point in both directions until they finally disappear at points a little distance away from the part of the broach adjacent to the cut ends of the ring at which part the periphery of the mandrel bears on the inner surface of the rings. The metal on the inner surface of the rings is indented and stretched by the projections J in a 10 gradually diminishing degree in both directions from the point opposite to the cut ends, and the desired spring is thus imparted to the rings.

The example shown in Fig. 3 differs from 15 that hereinbefore described only in that the projections J are in the form of teeth gradually diminishing in effective radial depth from the maximum acting, as hereinbefore described, on the inner surface of the rings 20 B, in the holder A, at the point opposite to the cut ends thereof, and held in recesses K in the periphery of the broach.

As shown in Figs. 4 and 5, when the rings B are to be contracted they are placed around 25 a solid holder L and held in place by a cover plate C and a hollow broach D, E, with the eccentrically placed ball projections J on its inner periphery, is used. Thus on pushing the broach over the rings the projections 30 bear on the outer surface of the rings instead of the inner surface, the broach being so placed relative to the rings that the maximum projection bears on each ring at the point opposite to the cut ends thereof.

35 What I claim is:—

1. In the manufacture of cut or split spring packing rings for pistons and the like, a holder to receive the rings and a tool comprising a body portion carrying projections arranged eccentric to the body thereof in such manner that when applied to the rings the maximum projection bears on each ring at the point opposite to the cut ends thereof, the projections gradually diminishing from this point in both directions until they finally disappear at points a little distance away from the part of the tool adjacent to and adapted to bear upon the cut ends of the rings, as described.

40 2. In the manufacture of cut or split spring packing rings for pistons and the

like, a holder to carry the rings, a tool comprising a body portion, projections thereon in the form of steel balls held in a groove eccentric to the body of the tool, the tool being so applied to the rings that the maximum projection bears on each ring at the point opposite to the cut ends thereof, the projections gradually diminishing from this point in both directions until they finally 55 disappear at points a little distance away from the part of the tool adjacent to and adapted to bear upon the cut ends of the rings, as described.

3. In the manufacture of cut or split 60 spring packing rings for pistons and the like, a hollow holder in which the rings are laid, a tool comprising a body portion, projections arranged eccentrically on the outer periphery thereof, the tool being so forced 70 through the rings that the maximum projection bears on the inner surface of each ring at the point opposite to the cut ends thereof, the projections gradually diminishing from this point in both directions until they finally 75 disappear at points a little distance away from the part of the tool adjacent to and adapted to bear upon the cut ends of the rings, as described.

4. In the manufacture of cut or split 80 spring packing rings for pistons and the like, a hollow holder in which the rings are laid, a tool comprising a body portion, projections on the outer periphery thereof in the form of steel balls held in a groove eccentric 85 to the body of the broach, the broach being so forced through the rings that the maximum projection bears on the inner surface of each ring at the point opposite to the cut ends thereof, the projections gradually diminishing from this point in both directions until they finally 90 disappear at points a little distance away from the part of the tool adjacent to and adapted to bear upon the cut ends of the rings, as described.

95 In testimony whereof I have signed my name to this specification, in the presence of two subscribing witnesses.

GEORGE WOODVINE.

Witnesses:

ANDREW SCOBIE,
B. K. HOUSTRON.
